FIG. 5.

Patented July 3, 1923.

1,460,398

UNITED STATES PATENT OFFICE.

AUGUST M. AUGENSEN, OF GRAND JUNCTION, COLORADO.

CAN-CAP-SEAMING APPARATUS FOR VARNISH CANS, ETC.

Application filed April 22, 1920. Serial No. 375,680.

To all whom it may concern:

Be it known that I, AUGUST M. AUGENSEN, a citizen of the United States, and a resident of Grand Junction, in the county 5 of Mesa and State of Colorado, have invented certain new and useful Improvements in Can-Cap-Seaming Apparatus for Varnish Cans, Etc., of which the following is a full, clear, and exact specification.

10 My invention is concerned with can cap seaming machinery for varnish cans, etc., and is designed to produce a novel power operated device of the class described which is at all times under the control of the operator, so that it can be more certainly manipulated than can the prior power operated devices with which I am familiar, and thus be employed in capping cans of shapes which could not readily be handled by ordinary 20 means.

To these ends, it consists of the novel structure hereinafter fully described and particularly pointed out in the claims.

To illustrate my invention I annex hereto 25 two sheets of drawings in which the same reference characters are used to designate identical parts in all the figures of which—

Figure 1 is a view partly in central longitudinal section showing a part of my invention as applied to a hand tool;

Fig. 2 is a section on the line 2—2 of Fig. 1;

Fig. 3 is a vertical section through a can and cap of the character for which my invention is designed, before the cap has been secured in place;

Fig. 4 is a similar view after the cap has been secured in place;

Fig. 5 is a side elevation of my invention 40 in its preferred form applied to a power operated machine; and

Fig. 6 is an enlarged detail of the same.

Some forms of cans, such for instance as varnish cans, have a generally square or 45 rectangular body 10 with a funnel 11 secured in one corner thereof through which the can is filled, and after it is filled, a cap 12 is placed over the open upper end of the funnel with the downwardly projecting flange 13. To seal the same, the flange 13 must be turned in, as seen in Fig. 4, and the object of my invention is to produce an apparatus which will readily perform this 50 function.

55 In Figs. 1 and 2, I have shown a hand tool adapted for this purpose, which consists pri-

marily of a supporting shaft 14, which has secured on its lower end a head 15, generally circular in cross section, but provided with a plurality of pairs of ears 16 in which 60 are fulcrumed the levers 17 upon the fulcrum pins 18. These levers have the seaming rolls 19 journaled on their lower ends, and preferably held in place by having the flange 20 on their upper end resting in all positions of 65 the apparatus upon the upper edge of the flange 21 of the clamping chuck 22, which consists of a rotary member circular in its horizontal cross section and having the under surface 23 of the proper shape to fit 70 snugly in the top of the particular cap 12 for which it is designed. The upper end 24 is reduced and fits in a correspondingly shaped circular recess 25 in the under side of the head 15, and is preferably provided 75 with an annular groove 26, semicircular in cross section, with which groove cooperate one or more pins 27 driven into the head 15 so as to engage said groove 26 and hold the chuck in place while not interfering with its 80 rotation in the head. In order to diminish the friction resulting from any relative rotation of the head 15 and the chuck 22, I preferably interpose a set of ball bearings 28 between the groove bearing rings 29 and 85 30 seated respectively in the under side of the head 15 and on the upper side of the chuck 22. For hand use, the shaft 14 has the handle 31 secured on the reduced upper end 32 thereof, as by the screw 33, while 90 a sleeve 34 having the flaring conical end 35 terminates the lower end thereof in position so that as the sleeve is raised by pulling on the handle 36 secured on the upper end thereof, the cone 35 will force the upper 95 ends of the levers 17 outward bringing the seaming rolls 19 into the proper position to crimp the flange 13 to the position shown in Fig. 4 when the shaft 14 is turned. A helically coiled expanding spring 37 is 100 interposed about the shaft 14 between the handles 31 and 36 so as to keep the sleeve down in position where the chuck 22 can be readily placed on the top of the cap 12. When this is done, the operator presses 105 down on the handle 31 at the same time with his fingers drawing up the handle 36 so as to force the crimping rolls 19 inward, and then turns the handles and thereby the shaft 14. The pressure of the chuck 22 110 on the cap holds it from turning, and the rolls 19 consequently roll around on the

flange 13 and produce the desired crimping effect.

Where my invention is applied to a power machine, I employ the base 38, which is preferably mounted on wheels or rollers 39 and has the central hollow standard 40. Secured to the side of the standard is the bracket arm 41 which has the vertical bearing sleeve 42 to accommodate the tube 43 mounted to slide up and down therein and having one end of the lever 44 pivoted to its lower end. This lever 44 is fulcrumed to the standard 40 at 45, and has the link 46 pivoted to its other end and extending down to a treadle 47 fulcrumed on the base 38 at 48. The supporting chuck 49, which preferably takes the form of a disk, flat on its upper surface, and with a flattened conical under side, is secured on the upper end of the rod 50 which has a plurality of apertures 51 therein through which a pin may be passed in connection with a pair of apertures in the tube 43 to regulate the position of the head of the supporting chuck 49.

A motor 52 may be secured on the base 38 and has the spur gear pinion 53 on its armature shaft meshing with the spur gear wheel 54 secured on the driving shaft 55 journaled in the bearings 56 projecting upward from the base 38. A belt pulley 57 secured on the other end of the shaft is connected by the belt 58 with a larger belt pulley 59 secured on the driving shaft 60 which is journaled in the bearings 61 and 62 formed on the upper end of the generally hollow head 63 secured on the top of the standard 40. The shaft 60 is preferably mounted so as to have a slight longitudinal movement in the bearings 61 and 62 so as to bring the beveled friction wheel 64 onto or out of engagement with the corresponding beveled friction wheel 65 secured on the upper end of the shaft 14^a. This shaft 14^a is journaled in the vertical bearing 66 formed in the bracket 67 projecting from that side of the head 63. The engaging surfaces of the friction wheels 64 and 65 are preferably covered with rawhide or some other suitable material to produce the desired friction. The movement of the shaft 60 is controlled by the lever 68 fulcrumed in the frame 63 at 69 and having its forked upper end co-operating with the annular groove 70 formed in the hub of the wheel 64, which might be splined on the shaft 60 instead of being rigidly connected thereto, in which case the shaft 60 need not be longitudinally movable in its bearings. The lower end of the lever 68 has the anti-friction roller 71 which is engaged by the cam surface 72 on the bar 73 which is mounted to slide, as shown, in the bearings 74 and 75 formed in the sides of the head 63. A short link 76 is pivoted at one end to the slide 73, while its other end is pivoted to the lever

arm 77 on the hollow inside of the head 63, which arm 77 is secured to the rock shaft 78 journaled in said head and having one end extending outside thereof so that the operating handle 79 can be readily secured thereto. The shaft 14^b, instead of having the head 15^a directly secured thereto, preferably has a tapering socket 80 in its lower end which is adapted to receive the tapered end 81 of the shaft 14^b, upon which slides cone 35^a which has the annular channel 34^a at its upper end adapted to receive the forked end 82 of the lever 83 which is fulcrumed at 84 between a pair of ears 85 extending downward from the under side of the head 63. A lever 86 is journaled on the same fulcrum and has an arm 87 extending under the lever 83 so that a set-screw 88 screwed through the arm 87 serves to regulate the position of the lever 83 to a nicety. The lever 86 has the anti-friction roller 89 in its upper end adapted to co-operate with the cam surface 90 formed on the under side of the bar 73. The levers 17^a are employed as before, but with the power operated head, a pair of these levers and crimping rolls 19^a are sufficient, whereas I preferably employ four with the hand operated device. The clamping chuck 22^a is the same as before and is secured to rotate in the head 15^a as before, but I may place the ball bearings 28^a between the top of the reduced portion 24^a and the bottom of the socket 25^a.

The fundamental operation of the power operated device is the same as the hand operated device, only it will be understood that the can 10 is placed on the supporting chuck 49 after which the pedal 47 is depressed to raise the chuck 49 to bring the cap 12 in engagement with the clamping chuck 22^a. This being done by the foot lever while the can 10 is free to be manipulated by the hands, it is possible to position the clamping chuck accurately on the cap 12 in spite of the eccentric location of the funnel, a thing that would be very difficult if not impossible to do if the movement of the supporting chuck was by power. When the can is positioned and clamped between the chucks 22^a and 49, the lever 79 is swung to pull the bar 73 downward, and this movement first causes the cam 72 to engage the roller 71 on the end of the lever 68, to bring the wheel 64 in operative engagement with the wheel 65 which starts the head 15^a to rotate. The further movement of the bar 73 causes the cam surface 90 to engage the roller 89 and swing the lever 86 to in turn swing the lever 83 to lift the cone 35^a and swing the rolls on the levers 17^a inward to engage the flange 13, so that the continued rotation of the rolls 19^a will serve to crimp cap as before.

While I have shown and described my

invention as embodied in the form which I at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States is:

- 10 1. In a device of the class described, the combination with a frame, of a vertically movable supporting chuck upon which the can rests, an aligned clamping chuck to engage the seated cap free to rotate but held from vertical movement, crimping rolls associated with the clamping chuck, and manually controlled means for continuously rotating said rolls about the cap for any desired length of time.
- 15 2. In a device of the class described, the combination with a frame, of a supporting chuck and a clamping chuck, means for moving said chucks relatively to secure a can between them, crimping rolls associated with the clamping chuck, and manually controlled means for continuously rotating said rolls about the cap for any desired length of time, said manually controlled means operating independently of the relative position of the chucks.

3. In a device of the class described, the combination with a frame, of a supporting chuck and a clamping chuck, means for moving said chucks relatively to secure a can between them, crimping rolls associated with the clamping chuck, a driving shaft, a driven shaft supporting the crimping rolls, and means for moving the crimping rolls inward for the purpose described independently of the relative movement of the chucks.

4. In a device of the class described, the combination with a frame, of a supporting chuck and a clamping chuck, means for moving said chucks relatively to secure a can between them, a vertical shaft, crimping rolls movably supported from the lower end of the shaft, a friction wheel on the top of the vertical shaft, a horizontal shaft, a friction wheel on its end adjacent the first friction wheel, and a lever to move the horizontal shaft to bring the friction wheels into engagement.

5. In a device of the class described, the combination with a frame, of a supporting chuck and a clamping chuck, means for

moving said chucks relatively to secure a can between them, a vertical shaft, crimping rolls movably supported from the lower end of the shaft, a friction wheel on the top of the vertical shaft, a horizontal shaft, a horizontally movable friction wheel on its end adjacent the first friction wheel, a cone slidable on the vertical shaft to move the crimping rolls toward the cap, a lever co-operating with the cone, a lever co-operating with the horizontally movable friction wheel and a cam slide co-operating with said levers

6. In a device of the class described, the combination with a frame, of a supporting chuck and a clamping chuck, means for moving said chucks relatively to secure a can between them, a vertical shaft, crimping rolls movably supported from the lower end of the shaft, a friction wheel on the top of the vertical shaft, a horizontal shaft, a friction wheel on its end adjacent the first friction wheel, a cone slidable on the vertical shaft to move the crimping rolls toward the cap, a lever co-operating with the cone, a cam slide co-operating with the lever, and a manually controlled lever for moving said cam slide.

7. In a device of the class described, the combination with a frame, of a supporting chuck and a clamping chuck, means for moving said chucks relatively to secure the can between them, a vertical shaft, a head carried by the lower end of said shaft in which head the clamping chuck is mounted to rotate, levers mounted on said head, crimping rolls on the lower ends of said levers, a friction wheel on the upper end of the vertical shaft, a horizontal shaft, a friction wheel on its end adapted to engage the first mentioned friction wheel, a cone on the vertical shaft engaging the ends of the levers on the head, levers for moving said cone vertically, a lever for moving the horizontal shaft, a cam slide adapted to co-operate with the last mentioned levers, and a handle connected to said cam slide, substantially as and for the purpose described.

In witness whereof, I have hereunto set my hand and affixed my seal, this fifteenth day of April A. D. 1920.

AUGUST M. AUGENSEN. [L. s.]

Witnesses:

CHARLES B. RICH,
J. W. VANNICE.
